(57) **CLAIM**

The ornamental design for a pneumatic radial tire, as shown
and described.

DESCRIPTION

FIG. 1 is a perspective view of a pneumatic radial tire in
accordance with the invention;

FIG. 2 is a front elevation view thereof;

FIG. 3 is a side elevation view thereof; and,

FIG. 4 is a partial front elevation view thereof, shown at an
enlarged scale.

The broken lines depict environmental subject matter only
and form no part of the claimed design.
